UNITED STATES PATENT OFFICE.

BENJAMIN F. CALDWELL AND WILLIAM F. PETERSON, OF WHEELING,
WEST VIRGINIA.

METHOD OF PAINTING SHEET-METAL ROOFING.

SPECIFICATION forming part of Letters Patent No. 374,112, dated November 29, 1887.

Application filed June 2, 1887. Serial No. 240,077. (No model.)

To all whom it may concern:

Be it known that we, BENJAMIN F. CALDWELL and WILLIAM F. PETERSON, citizens of the United States, residing at Wheeling, in the county of Ohio and State of West Virginia, have invented new and useful Improvements in Methods of Painting Sheet-Metal Roofing, of which the following is a specification.

10 Our invention relates to methods of painting metallic roofing; and the purpose thereof is to provide a novel method for applying the coating of paint to both sides of the continuous sheet or section without the necessity of turning the same, and leave it in a convenient position for rapid drying, the injury caused by dust and dirt adhering to the wet paint, the difficulty of turning the extended section, and the necessity for greatly-extended floor-space 15 being by our invention entirely avoided.

Metal roofing is manufactured in sheets of a given size, usually about twenty by twenty-eight inches, and a number of these sheets are joined together to form a continuous section 20 fifty or sixty feet in length. In the manufacture of tin roofing it is necessary to unite the sheets in this manner in view of the economy of time and the convenience and facility of painting the metal, and the same may be said 25 in regard to iron roofing. These sections have heretofore been laid upon the floor at full length and painted. After the application of paint to one side they must be turned over, after drying, to expose the opposite side, and, 30 finally, must be allowed to remain until the paint is dry. The size and weight of the sections render them very unwieldy and cumbersome in turning, and the floor-space required for their accommodation is very extensive, 35 40 while the dust and dirt accumulating during the time required for the drying of the paint is a constant cause of injury. To avoid these objections and effect an economy of space and time as well as better work, we have devised 45 the method hereinafter set forth, which may conveniently be carried out by means of the apparatus shown in the accompanying drawings, in which—

Figure 1 is a side elevation of a machine for 50 practicing our invention. Fig. 2 is a plan view of the same.

In the said drawings the reference-numeral 1 designates any suitable frame supporting a shaft, 2, which carries a drum, 3. Within the same frame is journaled a shaft, 4, carrying 55 spools 5, upon which we wind link chains and balls 6 and 7, respectively. Upon the drum 3 is a lip, 8, and in using the machine we hook the bent end of the metal section 9 upon this lip. The ends of the chains are then hooked 60 over a second lip, 10, upon the same drum, and power being applied to the shaft through a pulley, 11, the roofing-section 9 is gradually wound upon the drum with the link chains interposed between the successive coils, the 65 chains being fed from the spools 5, as shown in the drawings. The metal may be painted and immediately rolled up; but in either case it is allowed to remain upon the drum until the paint is dry, the chains allowing a free circulation of air over every part of both surfaces. 70

Instead of the form of chain shown and described, any chain, cord, or wire may be used, provided it has at suitable intervals blocks, balls, or similar devices which will support 75 the coils of roofing with sufficient space between to permit the passage of air; or ordinary chains or perforated belts might be employed without special construction, the only conditions being that they shall support the 80 coils in such manner as to leave a space between them and that they shall not materially obstruct the circulation of air. The chains are arranged at a little distance from the ends of the coil, as shown in Fig. 2, and we may 85 employ two, three, or more, according to the width of the section.

It will readily be seen that our invention may be practiced by any form of mechanism or without any apparatus whatever, since the 90 metal may be painted and rolled up by hand in a similar manner.

When wound upon a drum, the metal may be painted upon both sides at once, or it may be painted upon one side and allowed to dry 95 before it is unrolled and painted upon the other.

What we claim is—

1. The method herein set forth of painting and drying sheet-metal roofing, said method consisting in winding the sheet metal as it is 100 painted upon a rotating support, and at the same time winding in between the successive

2 coils of said sheet metal separating media, such as chains or their equivalents, substantially as described.

5 2. The method herein described of facilitating the painting and drying of sheet-metal roofing, which consists in winding the painted sheets or sections into a roll, and simultaneously therewith winding up with the sheets or sections interposed link chains, substantially
10 as set forth.

In testimony whereof we affix our signatures in presence of two witnesses.

BENJAMIN F. CALDWELL.
WILLIAM F. PETERSON.
